UNITED STATES PATENT OFFICE.

CHARLES S. HEFFELFINGER, OF LEBANON, PENNSYLVANIA.

FUEL-FEEDING DEVICE.

1,304,973.

Specification of Letters Patent. Patented May 27, 1919.

Application filed June 2, 1914. Serial No. 842,362.

To all whom it may concern:

Be it known that I, CHARLES S. HEFFELFINGER, a citizen of the United States, residing at Lebanon, in the county of Lebanon and State of Pennsylvania, have invented certain new and useful Improvements in Fuel-Feeding Devices, of which the following is a specification.

This invention relates to fuel feeding devices; and it relates more particularly to apparatus for feeding comminuted or powdered solid fuel to a fuel burner, said apparatus comprising conveyer means arranged to convey comminuted fuel in regulable quantity from a source of supply to a point of use, means for utilizing the fuel thus conveyed, and means most advantageously coaxial with said conveyer means for returning thereto any unused portions of the fuel.

20 The nature of the invention is more fully set forth in the accompanying description and claims and in the drawings forming a part hereof.

Fuel burners employing mixtures of air with powdered coal or the like are commonly used in many types of combustion apparatus such as furnaces of various kinds, rotary cement kilns, etc.; and within certain limits they have proved fairly satisfactory in practice. Considerable difficulty has been experienced, however, in accurately regulating and controlling the feed of powdered fuel to the burner or other combustion means so as to insure uniform character of the combustion flame under constant given conditions of operation, and also to provide for suitable variation in the character of the flame within limits, something which is often necessary in practice. Suitable disposition of the coarser particles of fuel which invariably accompany the powdered fuel and which are too coarse to be advantageously fed directly to a powdered fuel burner, is another serious problem which has not heretofore been satisfactorily solved.

One of the principal objects of the present invention is to provide apparatus in which the difficulties above noted are avoided and sundry new advantages are attained. By 50 means of the novel apparatus hereinafter disclosed, the character of the mixture supplied to the combustion burner may be maintained substantially uniform for any given conditions of operation; or it may be varied at will to give combustion flames differing as widely in character as the requirements of

the particular work in hand may call for. Another object of the invention is to insure that particles of fuel which by reason of their coarseness normally do not pass a given point in the apparatus are systematically caused to be again acted upon by the feeding device and to be further comminuted thereby to a greater or less extent. Another object of the invention is to provide apparatus of this character which is simple and compact in form, is economical of power, and which will operate successfully with little or no attention from an attendant over long periods of time. Other objects of the invention will appear as the description proceeds.

Briefly described, the complete apparatus of the present invention in its best form comprises regulable conveyer means for transferring comminuted fuel from a source of supply to a point of discharge from which the finer portions of the fuel are transported in a state of suspension, as by a current of a gas which is commonly air, to a suitable combustion device. Means are also best provided for trapping or retaining any relatively coarse fuel particles discharged by the conveyer means and for returning them to the conveyer means, the arrangement being such that such particles undergo more or less further comminution in the course of their return to and re-passage through the conveyer, and are thus eventually reduced for the most part to a sufficient degree of 80 fineness to be carried off by the air current.

The arrangement herein disclosed for returning coarse fuel particles to the aforesaid conveyer means, which may conveniently be termed the primary conveyer means, constitutes an important feature of the invention. In its best embodiment this arrangement comprises returning means or secondary conveyer means integral with or attached to the primary conveyer means in 100 such manner that the two constitute substantially a unitary mechanism or means capable of being driven as one mechanical element. In apparatus heretofore proposed for returning coarse fuel particles to the 105 conveyer of a fuel feeding device, the returning means has been a separate member or mechanism, either independently driven, or driven through gearing from the primary conveyer. The apparatus of the present invention enables marked saving in power over such arrangements, besides making for com-

pact and simple construction, and much more dependable and flexible operation.

In order to clearly explain the principles of the present invention, I have illustrated 5 in the accompanying drawings one embodiment thereof which has proved thoroughly satisfactory in actual use, and which I consider at present the best form of my invention. It is to be understood, however, that 10 the embodiment here shown is merely one example of apparatus coming within the purview of the invention; and that the invention is by no means limited to the specific arrangement of the apparatus parts here 15 shown. In the drawings,

Figure 1 is a longitudinal vertical section of the apparatus, parts being shown in elevation;

Fig. 2 is a bottom plan of a part of the 20 apparatus shown in Fig. 1;

Fig. 3 is a section taken on the line 3—3 of Fig. 1;

Fig. 4 is a side view on a slightly enlarged scale of a suction fan which may be 25 employed, a typical form of piping connections to its discharge being shown;

Fig. 5 is a detail section through the fan axis;

Fig. 6 illustrates a typical method of connection to a combustion furnace, on a smaller 30 scale;

Fig. 7 is a detail view in side elevation of the conveyer member drawn to a somewhat larger scale; and

Fig. 8 is a similar view of the conveyer 35 member in section.

Referring to the drawings, A denotes a feed hopper or other source of supply for powdered or comminuted coal, B denotes 40 generally a conveyer device arranged to receive fuel from the hopper, C represents generally conduit connections leading from the conveyer device, while D designates, broadly, means for drawing a current of 45 fuel-laden air from the conveyer device and the conduit, and for discharging the mixture to combustion apparatus of any suitable type.

The feed hopper is here shown as provided 50 with a downwardly extending conduit 10 flanged as at 11 and secured as by bolts 12 to flanges 13 of a similar conduit member 14 here shown as integral with a cylindrical conveyer casing 15, said conduit member and the sub-adjacent portion of the 55 conveyer casing thus forming a fuel magazine. Valve means of any convenient type, such as a sliding gate 16, are provided to regulate the flow of comminuted fuel to the conveyer casing. The conveyer casing and parts immediately connected therewith 60 may be conveniently supported by members 17 and 18.

Within the conveyer casing is revolvably 65 mounted a conveyer member 19 arranged to

convey fuel from the inlet 14 and to discharge the same into one end of a receiving conduit or chamber 20 which constitutes practically an extension of the conveyer casing and which may be integral therewith 70 or, as shown, secured thereto as by flanges 21 and bolts 22. The conveyer member 19 is most advantageously in the form of a cylindrical sleeve or shell provided exteriorly with spiral or screw blades 23 and 75 interiorly with spiral or screw blades 24. The exterior conveyer blades are arranged to work against the inner surface of the conveyer casing; while the inner conveyer blades work around a stationary shaft 25 80 which is secured by pin 26 to the supporting upright 18. It will be noted that the two sets of conveyer blades run in opposite directions. In the present example, the exterior conveyer blades or threads are right-hand threads; while those of the inner surface are left-hand threads. It is desirable 85 for present purposes that the conveying capacities of the outer and inner conveyers shall approximate equality; and one way of conveniently attaining this end is by providing double threads or blades on the inner surface of the conveyer shell, and by giving them a somewhat greater pitch than the threads of the outer conveyer. This 90 compound conveyer member may conveniently be an integral casting; although obviously it may be built up of inner and outer sections or in any other manner desired.

The conveyer casing extends some distance 100 to the right of the feed inlet 14 and terminates in a heavy bearing collar 27 secured as by bolts and flanges 28, 29, to the conveyer casing. The conveyer shell terminates in an elongated hub 30 shouldered as at 31 105 for engagement with bearing collar 27. The hub projects beyond the bearing collar, and a driving pulley 32, or the like, is splined to the hub at 33. Openings 34 near the right-hand end of the conveyer shell afford communication between the inner and outer surfaces thereof, and permit fuel returned by the inner or secondary conveyer to pass to the outer or primary conveyer.

In order to facilitate the feeding of residual material from chamber 20 into the secondary or return conveyer 24, a pilot or guiding device is provided, and comprises in this instance spiral conveyer blades 35 carried by shaft 36 which is secured as by a pin 37 to the conveyer shell so as to revolve therewith. The ends of revolvable shaft 36 and stationary shaft 25 may conveniently be in substantial abutment as here shown.

The discharge chamber 20 in the present example tapers slightly from its point of attachment to the conveyer casing 15 toward the outlet at its opposite end where it is secured as by bolts and flanges 38, 39 to the 130

conduit 40 through which comminuted fuel is carried from the conveyer by the fuel-entraining air current. Hand-holes 41 may be provided to enable ready inspection of the interior of the chamber and the removal therefrom of accumulated foreign material such as metal slugs, nails, and the like which are commonly found in coal and similar fuels. The conveyer casing may similarly be provided with inspection or clean-out doors 41^a. The conduit 40, after leaving the chamber 20, bends upward suddenly, a portion 42 thereof extending vertically and constituting a trap or separator in which the coarser particles of fuel, which may be carried along with the air current from the conveyer, have an opportunity to settle out by gravity. Such particles are deposited at the lower end of the conduit and work their way back into chamber 20 where they are directed by the pilot screw conveyer into the return conveyer which carries them to the other end of the apparatus and delivers them through openings 34 to the exterior or primary conveyer. After extending vertically for some distance as described, the conduit leads to the intake 43 of a suction or vacuum producing apparatus such as a centrifugal fan or blower 44 which discharges through conduit connections 45 and 46. The mixture of air and powdered fuel discharged from the blower may be consumed in any suitable type of combustion apparatus. In the present instance is illustrated an arrangement in which the powdered coal is blown into a supplemental air conduit 47 entering the wall 48 of a furnace. Preheated air may be supplied through conduit 47 in amounts regulable by means of valve or damper 49 to form with the powdered fuel blast a combustible mixture of any desired composition.

In Figs. 4 and 5 a preferred construction of the fan is clearly illustrated. The vanes of the fan or blower are best bent as at 50 to form lifting pockets and to engage more or less tangentially a supporting cone or hub 51 secured to shaft 52 which may be driven by a variable speed motor 53. This conical hub is located opposite the axial intake opening 43 of the fan rotor, and it therefore serves as a shield to protect the bearing 54 of the fan shaft from the finely divided fuel drawn in with air through the fan inlet. Discharge conduit connections 45, 46, may include a 3-way coupling member 55 at which point an auxiliary air conduit may be connected if desired, one opening in the coupling being closed in the present example as by a plug 56. More than one such set of connections may, of course, be connected to the discharge of the blower, the present arrangement being merely typical.

For the purpose of regulating the quan-

tity of mixture passing into the conduit 40, the conical chamber 20 may be provided at its smaller end with valve means such as a valve head 57 carried by a valve stem 58 which passes through the wall of conduit 70 40 and is threaded to engage a threaded boss 59. By suitably manipulating a controlling handle 60 on the valve stem, the valve head may be moved away from or toward the small end of the chamber 20, thus varying 75 within any desired limits the width of the annular space between the valve head and the walls of chamber 20, and in this way regulating the amount of mixture passing therethrough. In the present example the 80 valve head is shown as somewhat smaller than the smallest diameter of chamber 20, so that the outlet can not be closed by said valve head. This arrangement is not essential, however, and the valve head may be 85 arranged to entirely close the outlet if desired. Moreover, it is not absolutely necessary to provide regulating valve means of any description at this location, since efficient control can be otherwise attained as, 90 for example, by varying the speed of motor 53. The arrangement described is convenient, however, and provides an additional refinement in control. If desired, conduit 40 may also be provided at any convenient 95 point with a valved inlet 47^a whereby additional air may be drawn in if it is advisable at any time to supply a particularly lean mixture to the combustion burner.

In the arrangement here described, the 100 fuel coming from the feed hopper is subjected to an air current induced by suction of a fan, that is, to a current of air under reduced pressure. Ordinarily the air passing into the casing with the fuel going from 105 the feed hopper is sufficient in quantity for the purposes of the invention. It is obvious that supplementary air inlets, best controlled by valve means of some kind, may be provided in the conveyer casing at any convenient location, or in other parts of the apparatus adjacent thereto, as for example, in the feed hopper. Although the use of an induced or reduced pressure draft is distinctly advantageous, the invention is not 110 restricted thereto, and forced draft under any suitable degree of pressure may be employed in modified forms of the apparatus where desirable.

The operation of the apparatus above described is sufficiently obvious from the foregoing. The motor 53 being suitably energized, and the conveyer shell being revolved in the proper direction, fuel passes from the feed hopper into the conveyer casing whereupon it is moved toward the left at any desired rate of speed by the outer spiral conveyer blades. By the suction of the fan air is drawn into the conveyer casing from the feed hopper or other suitable source; and 120 125 130

such air passes in contact with the fuel and substantially parallel to its course on its way toward chamber 20. More or less air also passes through ports 34 of the conveyer shell and passes along the inner surface of the conveyer shell. This induced air current passes through the conical outlet of chamber 20, carrying with it in suspension the finer particles of fuel supplied to the chamber by the revoluble conveyer. The air current, after leaving chamber 20 is suddenly directed upwardly through vertical portion 42 of the air conduit; and during this portion of its travel, the combustible mixture is freed of a large part of whatever undesirably coarse fuel particles may have been carried by the air current from chamber 20. This portion 42 of the mixture conduit therefore serves as a kind of trap or separator in which the undesirably coarse fuel particles are gravitally eliminated from the mixture, falling back and collecting in chamber 20. These trapped or returned fuel particles are directed through the agency of the pilot screw 35 into the interior of the conveyer shell, whose conveyer blades act to work this returned material toward the right, discharging it through the ports 34 to the outer surface of the conveyer shell, by which it is reconveyed toward the left and again discharged into chamber 20. In this operation, the coarse particles are subjected more or less to a grinding and comminuting action, with the result that a considerable portion becomes sufficiently fine to be carried off by the air current and to pass the vertical trap in the conduit. It is to be noted that in the specific embodiment here illustrated, there is thus maintained a circulation of fuel in a circuit, and that the fuel may be subjected to the influence of an air current at substantially all points in this circuit or over an extensive portion thereof. As a result, the air current removes finely divided particles from the fuel to a greater or less extent not only at the point of discharge into chamber 20, but also to some extent throughout substantially the entire circuit in which the fuel is being moved. The outer and inner spiral conveyers while designed to operate fairly close to the adjacent surfaces of the casing and of the stationary shaft, respectively, may nevertheless permit passage of some air together with some of the more finely divided fuel. The major portion of the air current follows the spiral course of the fuel through the conveyer. In this way the feed of finely divided fuel to the air current is rendered substantially uniform for any given operating speed of the suction fan and of the conveyer. The fuel-laden air after passing the vertical portion of the conduit 42 is drawn into the fan inlet and is discharged from the fan casing under pressure and passes by way of the discharge connec-

tions to a powdered fuel burner of any ordinary or suitable design.

The arrangement of compound conveyer means arranged coaxially one within the other as here illustrated, I consider a very important feature of the invention, both because it enhances the uniformity of fuel feed, and consequently of mixture composition, in the particular form of the invention here shown; and further because it results in a very compact form of construction, a form of construction moreover which is very simple, economical of power and inexpensive both in first cost and in maintenance.

I believe it to be broadly new in apparatus for feeding fuel to a fuel burner to provide conveyer means of the type herein disclosed in which means are provided for moving material in opposite directions, the means for accomplishing this being located one within the other; more specifically to provide a conveyer sleeve or shell provided with spiral or screw blades on its outer and inner surfaces, the spirals being arranged in opposite senses.

It is evident that the apparatus here illustrated may be modified in mechanical details while still retaining the principal advantages inherent in the broad principles of the invention, and such changes are included within the scope of the appended claims.

What I claim is:—

1. Fuel feeding apparatus comprising means for conveying fuel in controlled amount from a source of supply to a point of discharge, means for subjecting the discharged fuel to a moving body of air, and means substantially coaxial with such conveying means for returning to said conveying means fuel discharged thereby but not carried away by the moving body of air.

2. Fuel feeding apparatus comprising means for conveying fuel in controlled amount from a source of supply to a point of discharge, means for subjecting the discharged fuel to an induced current of air, and means substantially coaxial with such conveying means for returning to said conveying means fuel discharged thereby but not carried away by the induced air current.

3. Fuel feeding apparatus comprising the combination, with means for supplying comminuted fuel, of a revoluble conveyer member arranged to transfer fuel therefrom to a point of discharge, means for subjecting the discharged fuel to a current of air, and a second revoluble conveyer member, substantially coaxial with the first for returning to the latter fuel discharged thereby but not carried away by the air current.

4. Fuel feeding apparatus comprising the combination, with a supply hopper for comminuted fuel, of a spiral conveyer arranged to transfer fuel therefrom to a point of discharge, means for subjecting the discharged

fuel to a current of air, and a second spiral conveyer substantially coaxial with the first and rigid therewith for returning to the latter fuel discharged thereby but not carried away by the air current.

5. Fuel feeding apparatus comprising the combination, with a supply hopper for comminuted fuel, of a spiral conveyer arranged to transfer fuel therefrom to a point of discharge, means for subjecting the discharged fuel to a current of air, a second spiral conveyer substantially coaxial with the first for returning to the latter fuel discharged thereby but not carried away by the air current, and means for facilitating feeding of such fuel to said second conveyer.

6. In fuel feeding apparatus, the combination, with a conveyer, a chamber into which said conveyer is arranged to discharge comminuted fuel, and means for removing fuel from said chamber for use, of a second conveyer arranged to transfer residual fuel from said chamber to the first conveyer, and means for facilitating feeding of such residual fuel to the second conveyer.

7. In fuel feeding apparatus, the combination, with a screw or spiral conveyer, a casing into which said conveyer is arranged to discharge comminuted fuel, of a second screw or spiral conveyer substantially coaxial with the first and arranged to return fuel from said casing to the first conveyer, and a pilot or auxiliary conveyer arranged to guide fuel to said second conveyer.

8. Fuel feeding apparatus comprising means for circulating comminuted fuel in a circuit, means for supplying fuel to such circulating means, and means for passing a fuel-entraining current of air in contact with such circulating means and with the fuel being moved thereby substantially throughout the entire circuit and beyond such circuit in the same general direction, and means for utilizing the fuel-laden air thus obtained.

9. Fuel feeding apparatus comprising a hopper for supplying comminuted fuel, a conveyer casing arranged to receive fuel from said hopper, compound conveyer means arranged to maintain continuous circulation of fuel within said casing, and means for passing a fuel-entraining current of air through said casing in contact with such fuel and substantially parallel to its course, in combination with means for utilizing the fuel-laden air thus obtained.

10. Fuel feeding apparatus comprising the combination, with comminuted fuel supply means, of a casing arranged to receive fuel therefrom, a hollow cylindrical device mounted to revolve within said casing, spiral conveyer blades on the outer surface of said device arranged to feed fuel from the supply means to a point of discharge, means

for subjecting the discharged fuel to a current of air, means adjacent the point of discharge for feeding into the interior of said conveyer device residual fuel not carried away by the air current, and spiral conveyer blades on the interior of said device arranged to return such residual fuel to the outer conveyer blades.

11. Fuel feeding apparatus comprising the combination with comminuted fuel supply means of a casing adapted to receive fuel therefrom, a hollow cylindrical member or shell revolvably supported within said shell, said casing being provided exteriorly with spiral conveyer blades arranged to move fuel from the supply means to a point of discharge and interiorly with spiral conveyer blades arranged in an opposite sense, means for revolving said shell, a discharge chamber arranged to receive fuel discharged by the exterior conveyer blades, a fan arranged to draw air through said discharge chamber, and auxiliary conveyer means revolvble with said shell and extending into the discharge chamber for directing residual fuel from said chamber to the interior conveyer blades, the latter being arranged to move such fuel toward the other end of the shell and to deliver it to the exterior conveyer blades.

12. Fuel feeding apparatus, comprising the combination, with fuel supply means, of conveyers disposed substantially one within the other, one of said conveyers being arranged to feed fuel from the supply means to a point of discharge, and means for subjecting fuel discharged from said conveyer to an air current to remove at least a part of such fuel, another of said conveyers being arranged to return to the first conveyer residual fuel not removed by the air current.

13. Fuel feeding apparatus comprising the combination with a casing provided with an inlet for comminuted fuel, of a hollow cylindrical structure mounted to revolve in said casing and provided with exterior and interior sets of conveyer blades, one set of blades being adapted to convey fuel from said inlet to a point of discharge for entrainment by an air current, and the other set being adapted to return to the first set fuel discharged thereby but escaping entrainment.

14. In an apparatus for feeding finely divided material, the combination of a magazine, a hollow feed screw extending through and out of said magazine, means for passing a current of air through said hollow screw to the outer end thereof, and means for returning to the magazine the surplus material not picked up by the air current.

15. In an apparatus for feeding finely divided material, the combination of a magazine, a hollow feed screw extending through and out of said magazine, means for passing

- 5 a current of air through said hollow screw to the outer end thereof, and means for returning to the magazine the surplus material not picked up by the air current, said 5 means comprising a return screw located parallel to the feed screw and extending back to the magazine.
16. Fuel feeding apparatus comprising revoluble conveyer means capable of moving 10 comminuted solid fuel in a circuit, means for supplying comminuted fuel to the circuit, and means for passing a current of air in contact with such fuel over a substantial portion of the circuit and beyond such circuit in the 15 same general direction, to obtain a mixture of air and fuel suitable for combustion purposes.
17. Fuel feeding apparatus comprising revoluble conveyer means capable of moving 20 comminuted solid fuel in a circuit, means for supplying comminuted fuel to the circuit, and means for passing a current of air in contact with such fuel and substantially parallel to the direction of fuel travel over a substantial portion of the circuit, to obtain a mixture of air and fuel suitable for combustion purposes.
18. Fuel feeding apparatus comprising a primary conveyer arranged to move fuel 25 from a source of supply to a point of discharge, means for subjecting the discharged fuel to a current of air, and a secondary conveyer arranged to return to the primary conveyer residual fuel not carried away by the air current, said conveyers being combined in a substantially unitary conveyer structure, and means for operating said conveyers.
19. Fuel feeding apparatus comprising a conveyer casing having a fuel supply inlet, a hollow conveyer shell revolubly mounted in said casing and provided with external
- conveyer blades adapted to move fuel from said inlet to a point of discharge, a chamber into one end of which said conveyer blades 45 discharge fuel, said chamber having an outlet at its opposite end, conveyer blades on the inside of said shell adapted to return residual fuel from said chamber to said external conveyer blades, and means for passing air in contact with both sets of blades and through the outlet of said chamber.
20. Fuel feeding apparatus comprising a hollow cylindrical conveyer member provided both on its inner and outer surfaces 5 with conveyer blades, the inner and outer sets of blades being arranged to move fuel in opposite directions and having substantially equal conveying capacities, and means for entraining fuel from said conveyer member by an air current.
21. Fuel feeding apparatus comprising a hollow cylindrical shell having interior and exterior sets of conveyer blades, the sets being arranged to move material in opposite 65 directions, a casing within which said shell is revolubly mounted, means for supplying fuel to said shell for transfer by one set of conveyer blades to the discharge end of the shell and means for subjecting such discharged fuel to an entraining current of air, the other set of conveyer blades being arranged to convey residual fuel from the discharge end substantially to the other end of said shell, suitable apertures being provided 75 in said shell to permit return of such fuel to their first-named set of conveyer blades.

In testimony whereof I have signed this specification in the presence of two subscribing witnesses.
